UNITED STATES PATENT OFFICE.

JACOB S. JAMMER, OF NEW YORK, N. Y., ASSIGNOR TO WESTERN ELECTRIC COMPANY, INCORPORATED, OF NEW YORK, N. Y., A CORPORATION OF NEW YORK.

AMPLIFYING REPEATER.

Application filed May 22, 1923. Serial No. 640,643.

This invention relates to an amplifying repeater such as employed in multiplex carrier current telephone and telegraph systems wherein different channel frequencies for transmission in one direction are grouped in a different frequency range from that employed for transmission in the opposite direction.

Among the objects of the invention are:

10 To produce a two-way amplifying repeater wherein the amplifiers for oppositely directed transmissions have different amplifying characteristics.

15 To produce a two-way amplifying repeater wherein the amplifying characteristics of the amplifiers for oppositely directed transmissions are particularly suited to the frequency range of the currents to be amplified thereby.

20 To produce a two-way amplifying repeater wherein the amplifying factor of the amplifier for the transmitted currents of the higher frequencies is greater than that of the amplifier for the transmitted currents of the lower frequencies.

25 To produce an efficient and economical two-way repeater.

The invention is illustrated as applied to a two-way amplifying repeater for use in a 30 multiplex carrier current telephone and telegraph system, but it is to be understood that it may also be applied to two-way amplifying repeaters for use in other signaling systems wherein the frequencies of the waves transmitted in one direction are in a different 35 frequency range than that embracing the waves transmitted in the opposite direction.

In the drawing—

Fig. 1 illustrates diagrammatically a two-way amplifying repeater having a two-stage amplifier for the group of higher frequency waves and a single stage amplifier for the group of lower frequency waves.

Fig. 2 illustrates diagrammatically a two-way amplifying repeater having a single stage amplifier for each group, the amplifying factor of one being greater than that of the other.

Fig. 3 shows curves representing the amplifying characteristics of the amplifiers of Figures 1 and 2.

Fig. 4 represents the gains of the respective amplifiers of the two-way repeaters shown in Figs. 1 and 2.

55 The two-way repeater of Fig. 1, comprising

ing two one-way repeating channels RE and RW, is adapted to couple two transmission line sections E and W.

The currents incoming to the repeater station from line section E are amplified in the repeating channel RE and the amplified currents are delivered to line section W. Likewise, the currents incoming from line section W are amplified in the repeating channel RW and the amplified currents are delivered to line section E.

The currents incoming from the line section W are of higher frequencies than those incoming from line section E, and, as will more fully hereinafter appear, the respective repeating channels are provided with frequency discriminating filters which direct the incoming currents to the proper channel.

It is well known that the characteristics of a line are such that the attenuation of the currents traversing it increases with an increase of frequency. The attenuation per unit length of line will, therefore, be greater for the currents incoming from line section W, than for those incoming from line section E.

Since the repeater is for the purpose of amplifying the attenuated currents and it is desirable that the outgoing transmissions of all frequencies from the repeater be at substantially the same energy level the attenuated currents of the higher frequencies should be amplified more than the lower frequencies.

The repeater channel wherein the higher frequency currents are amplified is, therefore, provided with amplifying means having a greater amplifying factor than that of the amplifier in the repeating channel for the lower frequency currents.

Among the advantages resulting from the use of a two-way repeater employing in the repeating channels thereof, amplifying means having amplifying factors selected in accordance with the frequencies of the currents to be amplified are—

Reduction in number and cost of amplifiers.

Reduction in cost of directional filters employed in the repeating channels.

The repeating channel RE includes input and output filters, EIF and EOF, an amplifier EA and an attenuation equalizer EAE.

The input and output filters EIF and

EOF may be low pass filters of the type disclosed in the patent to Raibourn, No. 1,413,357 granted April 18, 1922. They are designed to pass currents of the frequencies to be amplified in the repeater channel RE and to suppress currents of higher frequencies.

The amplifier EA may be of any well known type, but, as illustrated, is of the balanced type somewhat similar to that disclosed in Fig. 1 of U. S. patent to Colpitts, No. 1,128,292 granted February 16, 1915, but it must be adapted to handle the wide range of frequencies encountered in a multiplex carrier current system.

15 The input current to the amplifier EA may be regulated by a potentiometer 1.

The attenuation equalizer EAE, comprising an inductance 2 shunted by a capacity 3 connected in series with resistances 4 and 5, serves to so terminate the input filter EIF as to equalize the differences in line attenuations at the different frequencies of the currents to be amplified by amplifier EA. Thus the outputs from the amplifier 25 are of substantially equal value for the different frequencies.

The repeating channel RW includes input and output filters WIF and WOF, two amplifiers WA₁ and WA₂, connected in tandem by an interstage filter ISF, and an attenuation equalizer WAE.

The input and output filters WIF and WOF may be high pass filters of the type disclosed in the Raibourn patent, supra. 35 They are designated to pass currents of the frequencies to be amplified in the repeating channel RW and to suppress currents of lower frequencies. The interstage filter ISF is of the same type as the high pass filters WIF and WOF and passes only currents of the frequencies passed by these input and output filters.

A two-stage amplifier wherein the two amplifying structures are connected by a directional filter is disclosed and claimed in my copending application Serial No. 616,243, filed February 1, 1923.

The amplifiers WA¹ and WA², which are similar to amplifier EA, form a two-stage amplifier which has an amplifying factor greater than that of the single stage amplifier EA.

The input current to the amplifier WA₁ may be regulated by a potentiometer 6.

55 The attenuation equalizer WAE is similar to the equalizer EAE and serves the same general purpose.

Of course should occasion require it, additional stages of amplification may be introduced into each repeating channel.

The repeater of Fig. 2 is similar to that of Fig. 1, differing therefrom principally in that but a single stage amplifier is employed in each repeating channel. These

amplifiers, however, are so constructed that 65 inherently the amplifying factor of the west amplifier W₁A is greater than that of the east amplifier E₁A.

Whether an electronic valve amplifier has a high or low amplifying factor depends 70 upon the construction of the control electrode or grid and the spacing of the grid with respect to the cathode.

Thus an electronic amplifier having a grid of fine mesh spaced relatively close to the 75 cathode has a high amplifying factor. If the grid is of coarse mesh and spaced farther from the cathode, the amplifying factor will be lower.

Fig. 3 shows curves illustrating the difference in amplifying characteristics of the 80 east and west amplifiers employed in the repeaters shown in Figs. 1 and 2.

These curves are obtained by plotting the input voltage E_c as abscissæ against the output current I_r as ordinates.

Curve A represents the amplifying characteristic or factor of the west amplifier which amplifies the higher frequency currents, and curve B the amplifying characteristic or factor of the east amplifier which amplifies the lower frequency currents.

In Fig. 4, the line CD represents the attenuation characteristic of a transmission line section of approximately 250 miles of 95 open wire No. 8 BWG line for frequencies from 6.7 to 33.3 kilocycles. This line CD also represents the necessary net gain of the two-way repeater to compensate for the line attenuation.

Where the transmissions in opposite directions in a carrier telephone system are grouped, the channel frequencies for one direction may lie within the frequency range of 6.7 to 19 kilocycles and the channel frequencies for the opposite direction may lie within the frequency range of 21 to 33.3 kilocycles.

Inspection of Fig. 4 shows that currents of frequencies within the upper group of 110 21 to 33.3 kilocycles are attenuated more than currents having frequencies within the lower group. Consequently, a lower net gain is required of the repeating channel handling the lower frequency group than is 115 required of the repeating channel handling the upper frequency group.

The gross amplification of each repeating channel must be such as to compensate for the attenuation of the highest frequency 120 currents handled thereby.

Thus, the amplifier of the repeating channel RW provides a gross gain represented by the area DEFG. The attenuation equalizer WAE introduces a loss represented by the area DEH thereby leaving the net gain of the west repeating channel equivalent to the area DHFG.

The amplifier of the repeating channel RE provides a gross gain represented by the area JKLM. The attenuation equalizer EAE introduces a loss represented by the area CJK. Consequently, the net gain is represented by the area JCLM.

Thus, it will be seen that each repeating channel of the present two-way repeater provides only the amplification necessary to 10 compensate for the attenuation of the currents to be handled thereby.

It is well known that a two-way repeater will "sing" if the gain of its amplifiers exceeds the loss within the loop in which the 15 amplifiers are included. In practice, it has been found that the loss within the loop should exceed the gain to prevent the possible singing of the repeater. This loss is caused principally by attenuation which the 20 filters produce in currents outside their transmission range.

According to the usual practice, two-way repeaters are constructed so that the gross 25 gain of each repeating channel is the same. Since the net gain for the two repeating channels is not the same, it is necessary, according to present practice, to introduce a loss in the channel of which the lower net 30 gain is required, which means ordinarily that this required additional loss must be introduced by the filters or other means, thereby increasing materially and unnecessarily the cost of the repeater.

According to the present invention, each 35 repeating channel provides only the gross gain necessary to compensate for the attenuation of the highest frequency currents within the group handled thereby. Consequently, the loop gain is lower than in repeaters as previously employed. While the 40 loop loss must exceed the loop gain to prevent "singing" less loss is required by the repeater embodying the present invention. This loop loss is introduced by the filters 45 which may be less expensive as less energy is to be dissipated.

The invention set forth herein is, of course, susceptible of various other embodiments and adaptations.

The invention claimed is:

1. The combination of a transmission line 50 for transmitting in opposite directions a plurality of carrier currents comprised in respective frequency ranges, said line having greater attenuation for waves of higher 55 frequency transmitted in one direction than for waves of lower frequency transmitted in the opposite direction, and a two-way repeater comprising oppositely directed transmission paths, each path including means to 60 select a group of carrier currents, an amplifying means and an equalizer for compensating for the unequal attenuation produced by the line in the waves of the different frequencies comprised in the respective frequency ranges, the amplifying means in the path transmitting the waves of the higher frequencies having a greater amplifying factor than that in the path transmitting the waves of the lower frequencies, each 65 amplifying means having an amplifying factor such that the net gain over the loss introduced by the entire circuit including the line and respective equalizer is substantially the same for each frequency transmitted over the system. 70

2. A two-way repeater for coupling two transmission lines over which the currents transmitted in one direction are of higher frequencies than those transmitted in the 80 opposite direction, comprising two asymmetric repeating channels, input and output filters in each of said channels, an amplifier connected between the input and output filters in each of said channels, and equalizers in the respective channels for equalizing the differences in line attenuation in the different frequencies to be amplified by each repeater, the amplifying factor of the amplifier in the higher frequency channel being 85 greater than that of the other channel to effect the same net amplification in the higher frequency repeater channel and the line therefor and in the lower frequency 90 repeater channel and the line therefor. 95

In witness whereof, I hereunto subscribe my name this 18th day of May A. D., 1923.

JACOB S. JAMMER.
